UNITED STATES PATENT OFFICE.

CHARLES F. ATTWOOD, OF GRAND RAPIDS, MICHIGAN.

GREASE-PUMP.

1,295,670.

Specification of Letters Patent. Patented Feb. 25, 1919.

Application filed November 8, 1917. Serial No. 200,988.

To all whom it may concern:

Be it known that I, CHARLES F. ATTWOOD, a citizen of the United States, residing at Grand Rapids, in the county of Kent and

5 State of Michigan, have invented certain new and useful Improvements in Grease-Pumps, of which the following is a specification.

My invention relates to improvements in 10 pumps for handling heavy greases, and its objects are: first, to provide a means whereby the pump barrel will be completely filled with each upward stroke of the plunger, and the entire amount will be discharged 15 from the pump with each down stroke of the plunger; second, to wholly dispense with the use of valves in pump construction, and, third, to so construct my pump that it may be readily assembled or taken apart.

20 I attain these objects by the mechanism, construction and assemblage of parts shown in the accompanying drawing, in which Figure 1 is an elevation of my pump and a part of the oil or grease tank, showing the 25 pump and tank cut away at the connecting point to disclose the construction of the inlet and outlet of the pump. Fig. 2 is an elevation of the barrel of my pump disconnected from the standard. Fig. 3 is a transverse 30 vertical section of the same showing the construction of the plunger. Fig. 4 is a plan of the pump indicating how the position of the intake opening, or outflow opening may be determined. Fig. 5 shows the manner of 35 connecting the pump barrel to the pump standard so the barrel may be adjusted to carry the grease opening into intake or outflow position. Figs. 6 and 7 show means for applying a drain pipe.

40 Similar numerals refer to similar parts throughout the several views.

In the accompanying drawing 1 represents the oil or grease tank, which is of ordinary construction. 2 is my pump barrel 45 which is connected with the pump standard 7 by passing the lower end of the barrel downward through, or into the standard until the collar 11 rests upon the upper end of the standard. I then place the nut or bur 50 6 over the collar 11 and screw it onto the standard, as indicated in Fig. 5, so that a grease tight joint is formed, but the barrel may be readily revolved to change the position of the intake opening 9 from the inflow 55 pipe 8 around to the outflow pipe 10, as in

dictated by the dotted line at the right of Fig. 1.

The lower end of the pump barrel 2 is closed as at 2' to form an oil tight bottom to the barrel so that any and all grease taken into the barrel 2 upon the upward movement of the plunger 12 with the port 8 opening into the barrel, must, when the barrel is turned around into position to close the port 8, and open the port into 10, then 65 pressing the plunger downward, pass outward through the outflow tube 10.

The barrel 2 is made with an opening 9 through one side near the bottom or lower end of the barrel which is so positioned that 70 when desiring to draw grease from the main tank 1 into the pump barrel, the opening from the tank to the barrel is full and clear with no obstruction, while the opening to the outflow tube 10 is closed, and when the barrel is revolved around into position to discharge its contents through the discharge tube the opening from the tank is entirely closed. By this construction I am enabled 75 to dispense with the use of valves or other 80 obstructing elements in the path of the inflowing, or the outflowing grease, thus enabling me to handle the heaviest lubricating greases without danger of short-measuring the grease as it passes through the pump 85 and out at the opening indicated by the dotted lines 9'.

I provide for easily revolving the pump barrel by using a square rod for the plunger rod, as indicated at 4 in Figs. 1 and 3, which passes through a square opening in the top 5, so that the entire pump barrel must revolve with the handle 3, and to indicate the position of the intake opening 9 I place some 90 available symbol, as the arrow shown in 95 Fig. 4, in such position and place that it will always indicate, positively, the exact position of the said opening. The lower end of the plunger rod 4 may, in fact, should pass far enough below the plunger 12 as at 4' 100 to prevent the plunger from closing any part of the opening 9 when the plunger is in its lowest position, as indicated in Fig. 3.

In Fig. 6 I have shown an auxiliary barrel 13 that is secured to the standard 7 the 105 same as the barrel 2 is secured in Figs. 1 and 5. I provide this barrel with openings 8' and 10' that correspond with the openings 8 and 10 in the standard 7. This auxiliary barrel is used, simply, as a support for the 110

pump barrel 2, and is not only not essential to the proper working of the pump but adds to the cost of production, hence I prefer the construction shown in Fig. 1. At 14 I have 5 shown a brace that is connected at one end with the grease tank 1, and at the other end with the upper end of the pump barrel. In Fig. 1 this brace is shown in the form of a tube, as at 14', and is securely connected at 10 one end, with a band 13' that is made to encircle the pump barrel 2 so the pump barrel may be readily revolved therein. In Fig. 6 the brace 14 is secured to the auxiliary barrel 13, and in both instances it may be in 15 the form of an overflow tube or pipe through which any oil that may be forced by the plunger 12 may flow into the tank 1 and thus avert the danger of the grease being forced onto the pump handle or smearing 20 the top of the pump barrel, the barrel 2 being provided with an opening 15 into said pipe.

When using the auxiliary barrel 13 I provide for averting the danger of drawing 25 the pump barrel 2 upward with the upward movement of the plunger 12, by placing a flange 2" upon the lower end of the pump barrel, that will project outward the thickness of the auxiliary barrel and arranged to 30 revolve freely thereunder, with the pump barrel.

What I claim as new in the art, is:—

1. In a grease pump, an annular standard having a closed lower end and two lateral

openings near the lower end directly opposite each other, said standard screw threaded on the outer surface at the upper end, a screw threaded open nut arranged to screw onto the end of the standard and form a chamber between the end of the standard and the end 40 of the nut, a barrel passing through the nut and into the standard, and having an opening through one side registerable with the lateral openings in the standard, a collar around said barrel supported in the chamber at the end of the standard, a vertically movable plunger and plunger rod in the barrel, and means for imparting a revoluble movement to the barrel and the plunger rod. 45

2. In a grease pump, a standard having an inflow opening and an outflow opening on opposite sides, a barrel having the lower end closed and having an opening through one side alined with the openings in the standard, a flange around the barrel in position 55 to engage the end of the standard, a nut fitted to pass over said flange and be screwed upon the upper end of the standard, a plunger, a square plunger rod, a cap on the barrel having a square opening for the passage 60 of the plunger rod arranged to revolve the barrel with the plunger rod, and means for indicating the position of the side opening in the barrel.

Signed at Grand Rapids, Michigan, No- 65
vember 5, 1917.

CHARLES F. ATTWOOD.
